UNITED STATES PATENT OFFICE.

JOHN FENTON, OF INDIANAPOLIS, INDIANA.

TOE-WEIGHT.

SPECIFICATION forming part of Letters Patent No. 270,941, dated January 23, 1883.

Application filed August 25, 1882. (No model.)

To all whom it may concern:

Be it known that I, JOHN FENTON, of the city of Indianapolis, county of Marion, and State of Indiana, have invented certain new and useful Improvements in Toe-Weights, of which the following is a specification.

My said invention consists in certain improvements in that class of toe-weights wherein the weight can be adjusted so as to be lighter or heavier by the use of removable parts, as will be hereinafter more particularly described and claimed.

Said invention is intended as an improvement upon Letters Patent No. 244,386, granted 15 me, bearing date July 19, A. D. 1881.

Referring to the accompanying drawings, which are made a part hereof, and on which similar letters of reference indicate similar parts, Figure 1 is a perspective view of a horse's 20 foot and shoe with my improved toe-weight attached; Fig. 2, a front elevation of the shoe and weight; Fig. 3, a front elevation of the shoe and those portions of the weight which are not removable; Fig. 4, a rear elevation of the shoe 25 and weight; Fig. 5, a plan view of the shoe and the means by which the toe-weight is connected thereto, as seen when looking downwardly from the dotted line zz , the connecting angle-iron or knee being shown in section at 30 that point; Fig. 6, a cross-section of the weight and knee on the dotted line yy ; Fig. 7, a vertical section on the dotted line xx ; Fig. 8, a similar view to Fig. 7, except that the inner removable portion of the weight is removed; and 35 Fig. 9, a view similar to Fig. 7, except that the outer removable portion of the weight is removed instead of the inner portion.

In said drawings, the portions marked A represent a horse's hoof; B, a horseshoe; C, a 40 knee-shaped iron, by which a weight is connected to the shoe; D, a wedge for securing said iron to the shoe, and E F G the several portions of the toe-weight proper.

The shoe B, like that shown in my patent before referred to, is provided with a dovetailed groove to receive the knee C, and said knee is also similar to the knee shown in said patent, except that the space between the two parts of its lower portion is fitted to receive a wedge 50 instead of a screw.

The wedge D is fitted to force the branches

cc of the knee C apart and prevent said knee from being drawn out of the groove in the shoe B. It is secured in place by means of the removable portion of the weight, as shown most 55 plainly in Figs. 7, 8, and 9, said end being turned up alongside the knee C, so that said portions of the weight may cover the upper extremity thereof.

The portion E of the weight is secured to the 60 under side of the knee C by a rivet, e , and lugs $e'e'$, and rests upon or near the surface of the hoof. This portion of the weight is not intended to be removable, and, together with the knee C and its bolt C', constitutes the lightest 65 of my variable weights.

The portion F of the weight is secured to the outside of the knee C, either by the nut c' on the bolt C' being screwed directly against it, as shown in Fig. 9, or by being interposed between 70 said knee and the outer portion, G, as shown most plainly in Fig. 7. This portion, added to the portion E and knee C, constitutes the second or next heavier of my adjustable weights. 75

The portion G of the weight is secured in place by the nut c' on the bolt C', as shown in Figs. 7 and 8. It preferably has lips g , which enter notches in the sides of the part E to more 80 securely hold it in place. When used in addition to the portion E and knee C alone it constitutes the third or next to the heaviest of my adjustable weights. When both this and the portion F are used the combination makes the 85 fourth or heaviest of my adjustable weights.

My improved weight is used in the following manner: The knee C, bearing the part E, is first inserted in the dovetailed groove in the shoe B, which, so long as the key D is not inserted, is easily done from the front of the foot. 90 The key or wedge D is then driven in, spreading the ends cc of said knee and filling the dovetailed groove, so that said knee cannot be withdrawn. If it is desired to have a very light weight, it may be left in this condition, as 95 shown in Fig. 3. If it is desired to have a weight still light, but somewhat heavier than that just described, the portion F is added and the nut c' placed on the bolt C', as shown in Fig. 9. If it is desired to have a medium weight, 100 the portion G, instead of the portion F, is placed on the bolt, as shown in Fig. 8. If it is desired

to have a heavy weight, the portions F and G are both employed, as shown most plainly in Fig. 7.

As will be readily seen, by the use of these 5 several devices the weight may be varied as required. The weight or number of the removable portions may of course be increased or diminished, if found desirable.

The whole device can be readily removed 10 from the shoe by taking out the wedge or key D.

Having thus fully described my said invention, what I claim as new, and desire to secure by Letters Patent, is—

1. The combination of the shoe B, having a 15 dovetailed groove, the weight-supporting knee or angle C, the lower end of which is split into two parts, c c, and adapted to enter said groove, and the key or wedge D, which is adapted to be inserted between said parts c c and force 20 them apart, so that they cannot be withdrawn from said groove, and the end whereof is turned up alongside the knee C, and is thus adapted to be held in position by the weight, all substantially as shown and specified.

2. The combination of the shoe B, the weight- 25 supporting knee C, the key or wedge D, and the weight, the outer end of said wedge being inserted under said weight and held thereby, substantially as set forth.

3. The combination of the shoe B, the knee 30 C, connected to said shoe, having stud-bolts C', and an under plate, E, the removable portions, and the nut c', all arranged substantially as shown and specified.

4. The combination of the shoe B and the 35 knee C, bolt C', wedge D, plate E, and removable portions F and G, constituting a toe-weight, and means for attaching the same to the shoe, all substantially as shown and specified.

In witness whereof I have hereunto set my hand and seal, at Indianapolis, Indiana, this 21st day of August, A. D. 1882.

JOHN FENTON. [L. S.]

In presence of—

C. BRADFORD,
E. W. BRADFORD.
